SHOE SHINING MACHINE

Mathew H. Thornton, St. Paul, Minn.

Application September 9, 1932, Serial No. 632,300

17 Claims. (Cl. 15—35)

This invention relates to a shoe shining machine, and particularly to a machine for shining shoes which is automatic in operation and preferably one which operates in response to the deposit of a coin. With the large number of persons who now have their shoes shined regularly, large facilities are necessary. In spite of the large number of shoe shining places, persons desiring to have their shoes shined often find it difficult to obtain such service. This is particularly true on Sundays, holidays and in the evening hours. It is desirable, therefore, to have a machine which can be operated to shine shoes without the necessity of an attendant. Such machines can be placed in suitable locations and will always be accessible to the public.

It is an object of this invention, therefore, to provide a shoe shining machine which preferably will operate automatically upon the deposit of a coin and after operation of a suitable control means by the patron.

It is a further object of the invention to provide a machine which can be changed so as to suit either right or left shoes or changed to suit shoes of different sizes and styles.

It is another object of the invention to provide a machine having means for applying a blacking or polish to the shoe and a plurality of rotary brushes which are moved about the shoe to polish the same, together with a plurality of brushes which are moved across the top of the shoe to polish the toe.

It is still another object of the invention to provide a shoe shining machine having a novel form of control means and a novel form of means for applying a polish or blacking to the shoe.

It is also an object of the invention to provide a shoe shining machine having means for applying polish to the shoe and means for polishing the shoe, together with means which will protect the hose and other garments of the patron from being soiled by the blacking.

It is more specifically an object of the invention to provide a shoe shining machine having a plurality of brushes which are moved about the shoe, novel mechanism for driving these brushes, a guide means for the brushes conformable to various shapes in accordance with the size and style of the shoe, together with simple and novel means for driving and operating the various parts.

These and other objects and advantages of the invention will be fully set forth in the following description made in connection with the accompanying drawings, in which like reference

characters refer to similar parts throughout the several views and in which:

Fig. 1 is a substantially vertical and central longitudinal section through the machine quite a few of the parts being shown in side elevation; 5

Fig. 2 is a partial plan view showing similar parts in different positions in dotted lines;

Fig. 3 is a view in end elevation of the parts shown in Fig. 1, as seen from the left of said figure, part of the casing being shown in vertical 10 section;

Fig. 4 is a vertical section taken substantially on line 4—4 of Fig. 1, as indicated by the arrows;

Fig. 5 is a longitudinal section taken substantially on line 5—5 of Fig. 1, as indicated by the 15 arrows;

Fig. 6 is a partial plan view of a section of the guide track used;

Fig. 7 is a view in side elevation of the parts shown in Fig. 6; 20

Fig. 8 is a view in side elevation of the shoe support and guide means associated therewith, a portion of the guide track being shown in vertical section;

Fig. 9 is a horizontal section taken substantially on line 9—9 of Fig. 8, as indicated by the arrows; 25

Fig. 10 is a section taken on line 10—10 of Fig. 11, as indicated by the arrows;

Fig. 11 is a vertical section taken substantially on line 11—11 of Fig. 10, as indicated by the arrows; 30

Fig. 12 is a partial view similar to Fig. 11, showing the parts in a different position;

Fig. 13 is a partial view in side elevation of the parts shown in Fig. 11 and as seen from the right of said figure; 35

Fig. 14 is a view partly in vertical section and partly in side elevation of the control mechanism; 40

Fig. 15 is a view in front elevation as seen from the right of Fig. 14; and

Fig. 16 is a plan view of the parts shown in Fig. 14.

Referring to the drawings, particularly views 45

1, 3, 4, 8 and 9, a machine is shown comprising a foot plate 20 having a rear lower portion to accommodate the heel 21a of a shoe 21 and a front portion at a higher elevation adapted to support the instep and sole of the shoe 21. The 50 shoe 21 is shown as worn by the patron, the ankle portion of whose leg is shown at 22 and on which is shown a trouser portion 23. The plate 20 is carried by longitudinally spaced supports rising from another plate 24 beneath said 55

plate 20, plate 24 being carried by a suitable frame structure. Plate 24 has secured thereto a plurality of guide members 25 and while these might take various forms, in the embodiment of the invention illustrated they are shown as channel bars. These channel members are spaced circumferentially about the plates 20 and 24 as shown in Fig. 9, there being one at each end of said plates and three along each side. Said channels are placed at different levels so as to clear each other, the channel 25 at the rear end of the plate being at quite a low level and channel 25 at the front end of the plate being on top of the plate 24. Each channel member 25 has slidably longitudinally therein a bar 26, which bar 26 has secured thereto and upstanding therefrom a pin 27, the pins 27 moving through slots 24a formed to accommodate them in the plate 24. Pins 27 are adapted to engage the sole of the shoe 21 as well as the heel portion 21a thereof. The bars 26 are each connected at their outer ends to a section 28a of the guide track 28. Said track 28 is made of strips which are of considerable width and quite thin so as to be quite flexible, and said track has sections 28b which are slidable relatively to the sections 28a in overlapping relation thereto. Sections 28a are provided with flanges 28c forming a guide means for the sections 28b. As the members 26 move inwardly and outwardly the track 28 is thus moved to different shapes, the sections 28b being caused to slide relatively to the sections 28a to expand or contract the track. Each bar 26 has a reduced portion extending through the section 28a and is formed at its outer end with a head or enlarged portion engaging the outer side of the sections 28a so that said section is rigidly secured to the bar 26. Each bar 26 is formed at one side with gear teeth 26a and thus 40 constitutes a rack. Said rack is engaged by a gear segment 29 or 31. The segments 29 which are at the sides of the plate 20 are each provided with a hub 29a. Each of said hubs is journaled on a stud 30 secured at its upper end in the plate 24 and having the head 30a at its bottom supporting the hub and segment 29. The segments 29 at the sides of the plate 20 have formed thereon an arm 29b which extends inwardly. The gear segments 31 at the ends of the plate 50 20 have hubs engaging the top of the plate 24 and are secured to studs 32 having collars (not shown) seated and journaled in the plate 24 and having heads 32a at their lower ends. Levers 33 have hubs which are journaled on studs 55 32 below the plate 24 and these levers have laterally extending arms as shown in Fig. 9. The hubs of levers 33 are surrounded by torsion springs 34, one end of which is anchored in the plate 24 and the other end of which is anchored in the bottom of lever 33. These springs tend to move the levers 33 and segments 31 in a direction to move end bars 26 away from the shoe or plate 20. The hubs 29a also have torsion coil springs 35 surrounding them, one end of 60 which is anchored in the plate 24 and the other end of which is anchored in the segment 29. These springs are under tension so as to rotate segments 29 in a direction to move the bars 26 outwardly away from the shoe. The outward movement of the bars 26 at the sides and rear end of the shoe is limited by pin 36 which engages with the lug 25a at the top of the channel 25 when the bar reaches its limit of outward movement. In the case of bar 26 at the front 70 75 of the shoe the outward movement is limited

by pin 27 engaging the end of the slot 25b formed in the top of channel 25 at the front end of the shoe. Each of the levers 29b and 33 have secured thereto a tensile coil spring 37. The front lever 33 and two of the side levers 29b 5 adjacent the front have the springs 37 connected to a cable 38 running over a flanged sheave 39 and then being attached to a flanged drum 40 and adapted to be wound thereon. The two lever arms 29b adjacent the front of the 10 shoe at the other side have their springs 37 secured to a cable 41 which also passes over the sheave 39 and is secured to the drum 40. The rear levers 29b at the sides have their springs 37 respectively connected to a pair of cables 42 15 which run over a flanged sheave 43 and are then attached to the drum 40 so as to be wound thereon when cables 38 and 41 are wound thereon. The rear lever 29b has its spring 37 secured to a cable 44 which also runs over the sheave 43 20 and is likewise fastened to the drum 40 so as to be wound thereon with cables 41 and 42 as well as cable 38.

From the above description it will be seen that the bars 26 are normally moved outward by 25 the springs 34 and 35 and will be moved inwardly yieldingly by the cables described, when drum 40 is rotated in one direction. When the pins 27 contact the heel and sole of the shoe, springs 37 can yield, and all of the pins 27 will be brought 30 into contact with the shoe. This limits the inward movement of said pins and the bars 26 have then moved the track 28 so that it is shaped in accordance with the shape of the shoe to be 35 polished.

The track 28 at its rear has the narrow strip 28d extending across and secured to the rear movable sections 28b. A similar narrow strip 28d extends about the front of the movable section 28b. The rear sections 28b are extended 40 rearwardly in parallel spaced relation as shown in Figs. 5 and 9 and the track 28 then extends in permanent circular shape in a substantially circular portion, said track being supported by circumferentially spaced portions 46 extending from 45 brackets 47 secured to the frame. The track 28 is engaged at its top and bottom by the sheaves 48 having comparatively deep grooves therein tapering towards their bottoms and journaled on studs 49 secured in a bracket 50. Bracket 50 is pivotally 50 mounted on a horizontal pivot 51 to a member 52 which is rectangular in cross section at its upper portion, thus having side surfaces engaging the inner parallel surfaces of bracket 50 as shown in Fig. 10. Bracket 52 is bored to receive 55 a shaft 53 having secured to its upper end the hub 54a of a cylindrical brush 54, the same having the bristles 54b, the tufts of which project radially from hub 54a. The lower end of the tubular bracket 52 is provided with a fork 52a which is journaled for swinging movement on the inner ends of studs 56 threaded into the sides of the carrier bracket 57. There is thus 60 one of the carrier brackets 57 for each brush 54. While the number of brushes 54 might be varied, 65 in the embodiment of the invention illustrated there are four such brushes as shown in Fig. 5 where they are indicated by dotted lines and there are thus four of the brackets 57. Bracket 57 also includes the liquid receiving chamber 57a 70 closed by a threaded closing cap 57d. The bracket 57 as seen in plan in Fig. 10 is somewhat of U-shape and the chamber 57a extends about a flaring portion or opening 57b in the upper portion of the bracket as shown in Fig. 11. Cham- 75

ber 51a also extends to both sides of the bracket at the bottom thereof as shown in Fig. 11. The lower end of the shaft 53 has secured thereto a substantially spherical pulley 58. This pulley 5 is moved against a belt 59 of general trapezoidal shape having its side adjacent the pulley 58 somewhat concave. The belt 59 travels about a plurality of grooved pulleys 60 mounted on studs 61 secured in a plate 62 forming part of the 10 frame. Belt 59 at its ends runs over larger pulleys 63, the rear one of which is mounted on a shaft 64 journaled in a bracket 65 secured to plate 62. Shaft 64 has secured thereto a spiral or helical gear 66 meshing with a helical gear 67, 15 the latter gear being mounted on a shaft 68 journaled in bearings 69 and 70 and having at its other end a spur pinion 71. Pinion 71 is driven by the gear 72 secured to a shaft 73 having thereon a worm wheel gear 74 which in turn 20 is driven by a worm gear 75 secured to the armature shaft of the motor 76 mounted on the frame. The carrier bracket 57 shown in Figs. 10, 11 and 12 has a chamber 57c therein in which is fitted a bracket 77 having journaled therein a shaft 78 25 having secured thereto at its upper end a pulley 79 having a concave face. The pulley 79 engages the pulley 58 and is driven thereby. The lower end of the shaft 78 has a crank arm 80 secured thereto having a headed crank pin 81 secured 30 therein passing through the hub at one end of the link 82, said hub being journaled on said pin. The link 81 has a hub at its other end journaled on the pin 83 secured in a piston 84 reciprocable in a cylinder 85 forming part of the 35 bracket 77. Cylinder 85 has an opening 85a adjacent its closed end communicating with a check valve chamber 86 having therein a spring-pressed check valve 87 of conical form engaging the conical opening 85a. A tube 88 leads from 40 the valve casing 86 beneath the carrier bracket 57 and then upwardly along one side thereof. A tube 89 extends downwardly into the chamber 51a to a point closely adjacent the bottom thereof and said tube above bracket 57 joins tube 88 at 45 a sharp angle. A flexible tube 90 is secured to tube 88 beyond the junction of tube 89 therewith and another tube 91 is secured to the end of the flexible tube 90, said latter tube being shown as formed with a substantially circular bend. Tube 50 91 is provided with a spray nozzle 92 which will be disposed in position to spray liquid polish or cleaning fluid on the shoe. Tube 91 is connected by an arm 50a to bracket 50, and owing to flexible tube 90 nozzle 92, as well as brush 54 is moved 55 and controlled by track 28.

In the structure just described, it will be seen that when pulley 79 is driven, the piston 87 will be reciprocated by the crank arm 80. Air will be pumped in cylinder 85 by piston 87 and discharged through the tube 88. Cylinder 85 will be provided with an inlet check valve as usual, which is not shown. This air will pass through tube 88 and cause liquid to be drawn through the tube 89 and discharged through tube 91 and nozzle 92. In practice all the brackets 57 may not be provided with the brackets 77 and attached parts. The brackets 57 are carried on a pair of endless chains 93 and are secured to the links of said chain by oppositely disposed brackets 94 secured to said links and bolted to brackets 57 as shown in Fig. 11. The links 93a of chains 93 have projecting from opposite sides thereof cylindrical pins 95 adapted to travel in channel guide members 96 secured to the frame by bars 99 secured thereto and also secured to angle brackets

47 secured to plate 62 as shown in Fig. 11. The guide channels 96 are shaped somewhat similarly to the guide track 28 as shown in Fig. 5 and form a figure which is closed at its front end. At the rear the guide channels 96 extend in spaced relation substantially parallel to track 28 and also extend in circular formation inside of the track 28 being supported on the drum 45 and specifically by bars 99 secured to the brackets 47 already described. 5

The chains 93 are driven by sprockets 100 secured to shafts 101. Shafts 101 are mounted in bearings in the frame at their end portions and have secured thereto the spur gears 102. There are four sprockets shown at each side of each 10 chain. The shafts 101 at each side of the chains are arranged opposite each other and the gears 102 mesh with pinions 103 carried on central vertical shafts 104. Shafts 104 have beveled gears 105 at their lower ends and these beveled gears 20 mesh with beveled gears 106 secured to shaft 107 journaled in bearings on the frame. Shaft 107 extends longitudinally of the machine adjacent the bottom thereof and has secured thereto the gear 108 which meshes with and is driven by pinion 109 on shaft 73 which as already described is driven by worm 75 and worm wheel 74 from the motor 76. The gears 74, 75, 71, 72 and 108 and 109 are enclosed in the gear casing 110 bolted to the base plate 111 of the machine. 30

Shaft 107 extends to the forward end of the machine and has secured thereto a gear 112 meshing with a much smaller gear 113 which in turn meshes with another small gear 114 secured to shaft 115. Gear 113 is carried on a stud 116 secured in the end frame member 117. Shaft 115 has secured thereto a pulley 118 over which runs the comparatively wide belt 119. Belt 119 also runs over the spaced small pulleys 120 mounted on studs 121 secured in the end frame 117. Shaft 40 107 also has thereon a chain sprocket 122 over which runs a chain 123 also running over a sprocket 124 secured to a shaft 125 journaled in the end member 117 as well as in a bracket 126 which also carries a bearing for shaft 107 which rises 45 from the base plate 111. Sprocket 124 also carries a smaller sprocket 127 over which runs a chain 128 which also runs over a large sprocket 129 secured to a reel 130 having a hub 130a rotating on a stud 131 secured in the end member 117. Reel 50 130 has spaced rims 130b and four radially extending pairs of arms 130c. Arms 130c are bored to receive rods or plungers 132 engaged by compression coil springs 133 seated in the bore in the arms 130c and acting to move plungers 132 outwardly. Plungers 132 carry stop pins 133 moving in longitudinal slots 130d in the arms 130c to limit the outward movement of the rods 132. Rods 132 carry hubs 132a at their outer ends between which extends and in which is journaled a shaft 134 carrying a pulley 135. There are thus four of the pulleys 135. The shafts 134 extend at one side of the reel and have secured thereto the cylindrical brushes 136 having hubs 136a in which the bristles are secured. Belt 119 between the pulleys 120 travels over a plate 137. Belt 119 may be tightened by a belt tightener comprising a bell crank 138 having a hub journaled on the stud 139, one arm of which has secured therein a stud 140 70 on which is journaled a roller 141 adapted to engage belt 119. The other arm of bell crank lever 138 has a pin 142 extending through an arcuate slot 143 concentric with shaft 139 and which may be tightened and held in different positions in said 75

slot by having threaded thereon the thumb nut 144. Slot 143 is formed in the end casing wall 111d.

From the described structure it will be seen that when shaft 137 is driven, belt 119 will be rapidly driven. The shaft 125 will be driven and sprocket 129 and reel 130 rotated. This will carry the brushes 136 about the reel and successively into engagement with the toe portion of shoe 21. 10 As pulleys 135 travel about with the reel they are brought into engagement with belt 119 and thus rotated. This causes rotation of the brushes 136.

A control means is provided for the machine and in the embodiment of the invention illustrated this is shown as an operating lever 150 secured to a shaft 151 journaled in bearings 152 on the base plate 111. Lever 150 is shown as having a handle 150a at its end adapted to be conveniently grasped by the patron who will operate the machine. Lever 150 is normally in inclined position, as shown in dotted lines in Fig. 1, and is moved to said position by the torsion spring 154a. Cooperating with lever 150 is another lever 153 which is secured to a shaft 151 on which lever 150 is journaled, and this lever is normally urged to an angular position shown in Fig. 1 in dotted lines by a torsion spring 154 coiled about shaft 151, one end of which engages lever 153 and the other end of which engages the vertical standard 155. Lever 153 carries an electrical contact 155 engaging with another electrical contact 157 in a coin box 158 having leading therefrom a coin chute 159, the other end of which extends above the top plate 111a of the frame in position to have a coin deposited therein. Lever 153 also carries another electrical contact or switch arm 153b adapted to engage the contact or switch socket 155d on the standard 155 when lever 153 is in vertical position. The latter contacts are adapted to close the circuit of the motor 16 and start said motor. The standard 155 has secured to its top a pawl 160 which is pivoted on a headed stud 161 secured in said standard. Pawl 160 is held in the normal position shown in Fig. 16 by a torsion spring 162 coiled about pivot 161 having one arm secured in said pawl and another end secured in lever 153. Pawl 160 can normally swing in either direction and the same has one end projecting into the path of lever 150 as shown in Figs. 14 and 16. The swinging lever 153 also has secured to its top a swinging pawl 163 pivoted on the headed stud 164 secured therein, said stud having coiled thereabout a torsion spring 165 having one end secured in swinging lever 153 and its other end secured to pawl 163. Pawl 163 normally can swing in either direction and is held in the position shown in Fig. 16 by the spring 165. The standard 155 has an arm extending about lever 153 and this arm has mounted thereon a reciprocating latch or bolt 166 having a beveled end projecting along one side of the pawl 163 and having a portion extending into a bore in standard 155 which is reduced and has coiled thereabout a compression spring 167 seated in said standard and normally urging latch 166 outwardly. Lever 153 has mounted for sliding movement thereon a locking member 168 comprising a flat bar bifurcated at its upper end to have spaced portions 168a. Member 168 is held in sliding engagement with lever 153 by headed studs 169 extending through slots 168b in member 168 and threaded into lever 153. Member 168 is normally urged upwardly to the position shown in Figs. 14 and 15 by coiled compression spring 170 surrounding a headed pin

171 secured in the lug 153a projecting from lever 153 through a slot 168c in lever 168 and engaging a lug 168d. Member 168 is adapted to be locked in a depressed position and for this purpose a latch 172 is provided having a plunger seated in a bore 5 in bracket 173 secured to the side of member 168 by the screws 174 and normally urged outward by a spring 175. Latch 172 is constructed and arranged to be withdrawn by a solenoid 172a when the same is energized. Latch 172 is adapted to cooperate with a lug or keeper 153e projecting from lever 153. The member 168 at its lower end carries a projecting pin 176 adapted to be engaged by a cam arm 177 secured to a sleeve 178 journaled on shaft 151 between adjacent bearings 155b upstanding from the base of bracket 155. Sleeve 178 at its opposite end has secured thereto another cam arm 179 adapted to be engaged by a roller 180 journaled and carried on a headed stud 181 secured in a bracket 182 secured to the lower 20 chain 93.

The shaft 151 has secured adjacent one end a grooved semi-circular disk 183. This disk has secured at opposite sides respectively by screws 184 the ends of a cable 185, said cable running over drum or sheave 49. Means are provided for protecting the hosiery and garments of the patron while the shoes are being shined. In the embodiment of the invention illustrated this means is shown as comprising a pair of swinging members 186 and 187 of general rectangular shape, said members being pivoted respectively on the pivot members 188 and 189. Said members are provided with meshing gear segments 190 so as to swing in unison. Pivot 188 is surrounded by a torsion spring 191 having one end secured to the top plate 111b of the machine and its other end secured to the member 186. Spring 191 acts to move members 186 and 187 apart to substantially the dotted line position shown in Fig. 2. Said members have oblong slots cut therethrough extending from their meeting edges and these slots are overlaid with a compressible or yielding material 192 forming semi-elliptical strips about the edges of said openings and defining an elliptical 45 opening therebetween. The member 189 has secured thereto a lever 193 having a slot 193a adjacent its outer end in which is movable a pivot member 194 connected to a rod 195 extending through an aperture in the lug 155c on standard 155 and adapted to be engaged by lever 153 when it moves to vertical position. The various parts of the machine are enclosed in the casing comprising the base plate 111, the top plates 111a and 111b, said casing having the end walls 111c and 111d and the side walls 111e and 111f. The top plate 111b has an opening 111g through which the patron inserts his foot and shoe to place the same on the foot plate 20. The top plate 111b has an opening 111h therethrough to accommodate the movement of the lever 150. 50

In operation the machine will be at rest with the lever 153 in the position shown in dotted lines in Fig. 1. When a patron desires to have his shoes shined, he will place his foot on the plate 20, inserting the same forwardly through opening 111g. He will deposit the proper coin as directed in the coin chute 159. This coin will close a circuit through contacts 156 and 157 which will energize the solenoid 172a and withdraw latch 172 from beneath latch 168e. Spring 170 will now elevate the locking member 168 bringing the portions 168a alongside the pawls 160 and 163. The patron now grasps the lever 150 which is in inclined position alongside of lever 153 and swings 75

lever 150 upwardly to the full line position shown in Fig. 1. When lever 150 was swung down alongside of lever 153 by spring 154a to the dotted line position shown in Fig. 1, it moved past the latch pawl 160, said pawl swinging away from portion 168a to accommodate this movement. When the lever 150 is moved back to its vertical position, however, it engages the end of pawl 160 and said pawl cannot then swing owing to its other end 10 engaging the end 168a. Lever 153 is thus swung with lever 150 to vertical position owing to the engagement of pawl 160 with lever 150. When lever 153 is moved to vertical position, contacts 153b and 155d are engaged and the motor 76 is started. When the lever 153 is moved to vertical position, the pawl 163 snaps past the catch 166, said catch moving inward to accommodate its passage into the position shown in Fig. 16. This pawl cannot now swing out of engagement with catch 166 as it is prevented from swinging by the portion 168a engaging its long side. The lever 153 is thus now locked in vertical position by the pawl 163 and will be held in this position as long as locking member 168 is in its elevated position. 20 As lever 153 was swung to vertical position, it engaged rod 195 and moved the same to the full line position shown in Fig. 2. This, acting through lever 193 and gears 190 moves members 186 and 187 together so that the yielding portions 192 engage the ankle of the patron just above the shoe top. Only the shoe portion is now disposed below members 186 and 187 and the top 111b of the casing. When lever 153 was swung to vertical position, it oscillated shaft 151 and the disk 183. Disk 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

However, when the bracket moves onto the portion of the track adjacent plate 20, the pulley 58 of each brush engages the belt 59. Belt 59 is driven at high speed by the pulley 63 on shaft 64 which is in turn driven through gears 66 and 67 and through shaft 68. As the pulleys 58 engage the belt 59 they are rotated at high speed and thus rotate the brushes 54. After the second or cleaning brush 54 passes around the side of the shoe, polish is sprayed on the shoe by the nozzle 92 moving ahead of the next brush and the shoe is polished by the succeeding brushes 54 moving around the sides of the shoe. The spray nozzles 92 spray the entire shoe and the toe portion of the shoe is cleaned and polished by the brushes 136 mounted on the reel 130. This reel is driven at a speed synchronized with the movement of the chains 93 and before the first brush 54 passes around the toe of the shoe, the first brush 136 is moved over the top of the toe portion of the shoe and brushes any dust and loose dirt from the shoe. The next brush 136 passes over the toe of the shoe directly after the second brush 54 passes around the toe of the shoe. The third brush 54 then passes about the front of the shoe 25 and is followed by the third brush 136 which passes over the toe of the shoe. The fourth brush 54 now passes around the toe after which the fourth brush 136 passes over the toe of the shoe. As the reel 130 revolved in the direction indicated 30 by the arrows in Figs. 3 and 4, and the brushes 136 approach the shoe, the pulleys 135 carried on the reel and on the shafts which respectively carry the brushes 136 come in contact with the belt 119 running over the plate 137. The shafts 134 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

As above set forth, the pulley 58 drives the pulley 79 rotating shafts 78 and through the crank 80 reciprocating the piston 87. This discharges air through tube 88 and liquid is drawn by aspiration through tube 89 and discharged through the nozzles 92. This action, of course, continues only while pulley 58 is driven and as stated, this pulley is only driven while the brushes are moving around the shoe. When the brushes have all passed around the shoe, the roller 180 engages the cam 179 oscillating sleeve 178 and moving cam 177 against pin 176. Pin 176 is moved downwardly, thus moving downwardly locking member 168. When locking member 168 moves downwardly, the catch 172 moves past the keeper or latch 153e and latch 172 engages beneath keeper 153e, thus locking member 168 in depressed position against the tension of spring 170. When locking member 168 is depressed, portion 168a is moved away from pawl 163 and said pawl is now free to swing and no 75

longer locks lever 153 in vertical position. Said lever is then moved downwardly to the angular position shown in dotted lines in Fig. 1. The motor circuit is broken and the machine comes to rest. The machine is now in position to be again operated by the deposit of another coin as already described. When auxiliary lever 153 is thus swung downwardly, spring 191 separates the members 186 and 187. The patron can now readily remove his foot from plate 20 and will then place his other foot and shoe in position for the shoe to be shined. When lever 153 swings down to normal position, it rotates shaft 151 and thus rotates the disk 183 to its initial position, thus moving drum 40 to initial position permitting the slackening of cables 38, 41, 42 and 44 and permitting the torsion springs 34 and 35 to swing the segments 31 and moving the bars 26 outwardly. This separates and moves outwardly the pins 27 so that the shoe can be readily removed and another one then placed on the plate 20 and the pins again moved in when lever 150 is again swung to start the machine.

It will be seen that should the patron attempt to operate the machine without depositing a coin, that lever 153 cannot be raised by lever 150. Locking member 168 is depressed and if lever 150 is moved upwardly, it will not move lever 153 as the pawl 160 will merely swing about its pivot since it is not engaged by the portion 168a. The machine therefore cannot be operated unless the proper coin is deposited.

From the above description it is seen that applicant has provided a simple and ingenious shoe shining machine and one which will do the work effectively. The machine is largely automatic in action and operates to efficiently shine the shoe after the lever 150 is operated to bring the machine to proper position. It will be apparent that the device has a high degree of utility for the purpose intended.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

50 What is claimed is:

1. A shoe shining machine having in combination, a brush adapted to engage and brush the shoe, means for moving said brush about a shoe, a guide means for moving said brush in a path in accordance with the shape of the shoe, and means for conforming said last mentioned means to the shape of the shoe.

2. A shoe shining machine having in combination, means adapted to engage and shine a shoe, means for moving said first mentioned means about the sides of the shoe, a guide member for said first mentioned means causing it to move in a path in accordance with the shape of the shoe and means for changing the shape of said guide member.

3. A shoe shining machine having in combination, means adapted to engage and polish a shoe, means for moving said first mentioned means about the sides of the shoe, guide means extending about the shoe for determining the path of said first mentioned means, and means including members moved into engagement with the shoe to conform said guide means to the shape of the shoe.

4. A shoe shining machine having in combina-

tion, a means adapted to engage and polish the shoe, a swinging carrier for said means, means for moving said carrier about the shoe, a guide track, means engaging said track and connected to said carrier for moving the same to cause said first mentioned means to properly engage the shoe, and means for moving said track to change the shape thereof in accordance with the shape of the shoe.

5. A shoe shining machine having in combination, means adapted to engage and polish a shoe, means carrying said first mentioned means around the shoe, a guide track for said first mentioned means, a plurality of movable members secured to said track having means thereon movable against the shoe to conform said track to the shape of the shoe, and means for moving said members.

6. A shoe shining machine having in combination, means adapted to engage and polish a shoe, means carrying said first mentioned means around the shoe, a guide track for said first mentioned means, a plurality of movable members secured to said track having means thereon movable against the shoe to conform said track to the shape of the shoe, manual means for moving said members in one direction, and automatic means moving said members in the opposite direction.

7. A shoe shining machine having in combination, means adapted to engage and polish a shoe, means carrying said first mentioned means around the shoe, a guide track for said first mentioned means, a plurality of members spaced about the shoe for engaging the shoe, a slide carrying each of said members and connected to said track, a guide for said slide, springs for moving said slides in one direction, and manually operated yielding means for moving said slides in the opposite direction to cause said members yielding to engage the shoe.

8. A shoe shining machine having in combination, means adapted to engage and polish a shoe, means for moving said first mentioned means about the shoe, a guide means for determining the path of said first mentioned means, members engageable with the shoe at circumferentially spaced points thereabout to move said guide means in accordance with the shape of the shoe, and a common means for moving all of said members toward the shoe.

9. A shoe shining machine having in combination, a guide member for a shoe-engaging means comprising relatively movable sections slidably arranged in relation to each other, means connected to certain of said sections, and means for moving said last mentioned means in accordance with the shape of said shoe to cause relative movement of said sections and change the shape of said track.

10. A shoe shining machine having in combination, a support for the shoe, means for polishing the front portion of the shoe comprising a plurality of rotatable polishing members, a carrier rotatable on a horizontal axis above the shoe on which said members are mounted in spaced relation, a driving member for each of said members, a driven endless member and means for rotating said carrier and bringing said driving members successively into engagement with said endless member to drive said polishing members.

11. A shoe shining machine having in combination, a support for a shoe, means for applying liquid to said shoe, and a guard for protecting the garments of a patron comprising separa-

ble members adapted to clasp the foot or ankle of the patron just above the shoe.

12. A shoe shining machine having in combination, a support on which the shoe is placed, a cleaning brush movable around the sides of the shoe to engage said sides, a cleaning brush movable across the toe of said shoe, a first polishing brush movable around the sides of said shoe to engage said sides, a second finishing polishing brush movable around the sides of the shoe to engage said sides, a first polishing brush movable across the toe of said shoe, a second finishing polishing brush movable across the toe of said shoe, means for moving said first, third and fourth named brushes successively about the sides and toe of said shoe, means for moving the second, fifth and sixth named brushes successively across said toe and means actuating said last two means in synchronism to move said second mentioned brush across said toe immediately after said first mentioned brush moves about said toe to move said fifth brush across said toe immediately after said third brush moves about said toe and to move said sixth brush across said toe immediately after said fourth brush moves about said toe.

13. A shoe shining machine having in combination, a support on which a shoe is placed, a cleaning brush, a scrubbing brush, a first polishing brush, a second polishing and finishing brush, means for moving said brushes in succession around the shoe along the sides and toe thereof, a toe cleaning brush, a toe scrubbing brush, a first toe polishing brush, a second toe polishing and finishing brush, means for moving said last four named brushes in succession across the top of the toe of said shoe and means for actuating said last two means in synchronism to first move said cleaning brush around said shoe, then move said toe cleaning brush across the top of said toe then move said scrubbing brush around said shoe, then move said toe scrubbing brush across said toe, then move said first polishing brush around said shoe, then move said first toe polishing brush across said toe, then move said second polishing and finishing brush around said shoe and then move said second toe polishing and finishing brush across said toe.

14. A shoe shining machine having in combination, a support on which a shoe is placed, a cleaning brush, a first polishing brush, a second polishing and finishing brush, means for moving said brushes in succession about the sides and toe of said shoe, a carrier revoluble about a horizontal axis extending longitudinally of said shoe, a toe cleaning brush, a first toe polishing brush, a second toe polishing and finishing brush mounted on said carrier, means for rotating said carrier to move said last three named brushes transversely across the toe of said shoe in succession, means for rotating each of said brushes as it moves transversely across the toe of said shoe, means actuating said first mentioned means and means for so rotating said carrier in synchronism to move said cleaning brush

around the sides and toe of said shoe, then move said toe cleaning brush across the top of said toe, then move said first polishing brush around the sides and toe of said shoe, then move said first toe polishing brush across the top of said toe, then move said second polishing and finishing brush around the sides and toe of said shoe and then move said second toe polishing and finishing brush across the top of said toe.

15. A shoe shining machine having in combination, a support on which a shoe is placed, a cleaning brush, a scrubbing brush, a first polishing brush, a second polishing and finishing brush, means for moving said brushes in succession about the sides and toe of said shoe, means moving around said shoe for spraying cleaning fluid on said shoe in advance of said scrubbing brush, means moving around said shoe for spraying polish on said shoe in advance of said first polishing brush, a revoluble carrier mounted about said support, a toe cleaning brush, a toe scrubbing brush, a first toe polishing brush and a second toe polishing and finishing brush mounted on said carrier and means for actuating said first mentioned means and for rotating said carrier in synchronism to move said brushes so that said cleaning brush first moves around the sides and toe of said shoe, said toe cleaning brush then moves across the toe of said shoe, said first polishing brush moves around the sides and toe of said shoe, said first toe polishing brush then moves across the top of said toe, said second polishing and finishing brush then moves around said shoe engaging the sides and toe thereof and said second toe polishing and finishing brush then moves across the top of said toe.

16. A shoe shining machine having in combination, a support on which a shoe is placed, a dust removing brush, a scrubbing brush, a polishing brush, a second polishing and finishing brush, means for moving said brushes around said support and around said shoe in succession, means moving around said shoe and support for spraying a cleaning fluid on said shoe in advance of said scrubbing brush and means moving around said shoe and support for spraying polish on said shoe in advance of said polishing brush.

17. A shoe shining machine having in combination, a brush for operating on a shoe, means for moving said brush around said shoe to engage the sides thereof including the sides of the toe, a member extending in a closed path about said shoe, a spraying device movable around said shoe in advance of said brush and comprising a cylinder and reciprocable piston therein for pumping spraying fluid and a rotatable member connected to said reciprocating piston and engaging said last mentioned member to be rotated thereby, whereby said piston and spraying means are actuated.

MATHEW H. THORNTON.
